UNITED STATES PATENT OFFICE

EMIL M. SPRICH, OF ST. LOUIS, MISSOURI

SMOKE PIPE

Application filed July 8, 1929. Serial No. 376,621.

My invention relates to improvements in smoke pipes, and has for its primary object a smoke pipe which is so arranged that the smoker will have a cool smoke.

5 A further object is to construct a smoke pipe which is so arranged that the saliva entering the stem of the pipe from the mouth of the smoker will not be intermingled with the nicotine or other residue remaining or emanating from the tobacco while being smoked so that if such saliva be drawn into the mouth of the smoker no nauseating taste will result.

10 A still further object is to construct a smoke pipe, which has a tobacco container, an intermediate container, and an outer container, all communicating with each other, the outer container being adapted to contain a liquid, such as water or the like, which will not only 15 tend to keep the pipe cool but which will also have a tendency to prevent tobacco in the tobacco container or bowl from drying out in the event that the smoker does not consume all of the tobacco in the bowl. It very frequently happens that a smoker will lay his 20 pipe aside, permit it to go out and several hours afterward re-light the pipe. During this time, however, the heat from the burning coal of tobacco and also the heat absorbed by the pipe itself will dry out the remaining tobacco so that when the pipe is again lit, it will have a stale taste. In other words, my improved pipe will act, to a great 25 extent, as a humidor for any unconsumed tobacco remaining in the pipe thereby keeping it in a proper smoking condition.

In the drawings:

Fig. 1 is a longitudinal section of my improved pipe with a portion of the stem or mouth piece in side elevation;

Fig. 2 is a side view of my pipe;

Fig. 3 is a top plan view of the same;

Fig. 4 is a section taken on the line 4-4 of Fig. 3; and

Fig. 5 is a front elevation of the pipe.

In the construction of my device I employ an outer member 6, which is substantially in the shape of a flattened ovoid so as to provide a substantially flat top 7 and a flattened bot-

tom 8 on which the pipe can rest without danger of tipping over.

The rear end of the outer member 6 is provided with a screw threaded portion 7 on which a stem or mouth piece 10 is to be secured. The mouth piece 10 is provided with a bore 11, which extends longitudinally therethrough, and located in this bore and extending into the interior of the member 6 is a tube 12. This tube is preferably inclined 60 downwardly when the stem is in position so that in the event any saliva from the mouth of the smoker enters the tube 12, this saliva can drip down into the interior of the member 6.

65 The top 7 is provided with a thickened member 13, which is provided with a recess 14. This recess is adapted to receive the flange 15 of an intermediate member 16. This member is preferably rectangular in cross section and is smaller at its base 17 than at its upper end.

70 The intermediate member 16 is also provided with a tubular member 18, which preferably extends downwardly at an angle 75 therefrom so as to point toward the bottom of the member 6.

75 Carried by the member 16 and resting on the flange 15 is a tobacco container or bowl 19. This bowl is preferably frusto-conical in shape and is provided at or near its bottom with openings 20 through which smoke can pass and enter the intermediate member 16. The upper portion of the bowl is provided with a flange 21 which rests on the flange 15 and in such a manner that leakage of air is prevented. In other words, an airtight friction connection is provided between the upper end of the intermediate member 16 and that portion of the bowl 19 immediately under the flange 21. The bowl 19, however, is made readily removable for cleaning purposes.

80 The sides of the member 6 are preferably indented as indicated by the numeral 22 so as to be relatively close to the intermediate member 16 thereby leaving only a narrow passage 23 for smoke to pass.

85 The member 6 is adapted to contain a body of water or similar fluid 24, which is of such

depth that it will just about contact with the lower end of the intermediate member 16. It is essential, however, that not enough fluid be placed in the member 6 to enter either of the tubes 12 or 18, no matter in which position the pipe may be placed. The purpose of this is to prevent any of the fluid passing through either of these tubular members and dampening the clothes of the wearer when carrying the pipe in his pocket. It is my intention to make the members 16 and 6 of a very light metal or of any substance which can be readily molded, but which will not be readily affected by heat so that I may remove the stem 10 and the bowl 19 and place the containers 6 and 16 in hot water for boiling out purposes to remove any sediment or foreign matter which may accumulate therein.

The liquid is supplied to the interior of the member 6 by removing the stem 10 and then injecting the liquid through the screw threaded sleeve or projection 9, after which the stem is replaced.

The indented portion 22 of the outer member 6 may also be provided with corrugations 25 or any suitable roughening so as to form or provide a firm grip for the fingers.

From my construction it will be noted that the outer member 6 will not become heated even though the pipe is smoked very fast because the bowl 19 only contacts with the intermediate member 16 on its upper surface and the intermediate member 16 does not contact with the outer member 6 except at its flange. Therefore, these three members are substantially isolated from each other, there being a smoke passage 26 between the bowl 19 and the interior of the intermediate member 16, and as before mentioned the intermediate member 16 has a very slight contact with the member 6.

When using the device the operation is as follows:

The first step is to remove the stem 10 and supply a predetermined amount of water or other liquid to the outer member 6, after which the stem is again placed in position. The bowl 19 is then charged with tobacco and after the tobacco has been ignited, the pipe is smoked in the usual way, that is by drawing on the stem 10. This creates a partial vacuum in the container 6, which vacuum is communicated to the interior of the intermediate member 16 through the tubular projection 18. This vacuum in turn is communicated to the interior of the bowl 19 adjacent its bottom through the openings 20 causing air to be drawn down through the tobacco, which air intermingles with the smoke from the tobacco drawing the same into the intermediate container 16.

From there it passes out through the tubular member 18 into the container 6 above the water or liquid therein. The smoke during this passage having become cool will

have a tendency to descend and pass along the surface of the liquid. This liquid will then absorb any nicotine or other substances, which usually emanate from tobacco and pass off with the smoke permitting only clean smoke to pass into the stem and into the mouth of the smoker. Then, if the smoker should be what is known as a "wet smoker" that is one who permits saliva to pass into the stem, he will not draw any of these by-products of smoking into his mouth in the event the stem becomes heavily charged with saliva but he will draw only the saliva into his mouth. This will prevent the smoker from becoming nauseated, an occurrence which has deterred many smokers from using pipes, and should any saliva run down through the stem, it will drop into the liquid below but will not mingle, and cannot mingle, with the tobacco. Therefore, my pipe will remain sweet at all times.

When it is desired to clean the pipe, the stem and the bowl are removed and the outer member and intermediate member may then be placed into any suitable vessel containing a liquid and boiled out, it being essential, of course, that the outer and intermediate members be made of such material which will not warp or twist out of shape due to the boiling. In this way the pipe can be kept sweet at all times.

It is also believed that during the smoking of the pipe, and especially on account of the restricted passages at the side of the intermediate member, that a large portion of the smoke will be drawn through the liquid in the outer member thereby not only cooling the smoke but also eliminating any noxious matter which might be carried over. In fact, if found desirable, I may so construct the outer member that the side walls of the intermediate member will fit closely thereto so that all of the smoke will necessarily have to pass through the liquid in the outer member. This construction is only a slight modification of the device as disclosed in the drawings and consequently is not shown in detail. The bottom of the intermediate member may also be grooved or corrugated so as to provide a plurality of passages on the underside of the intermediate member for the passage of smoke without departing from the spirit of my invention.

Having fully described my invention, what I claim is:

1. A smoke pipe comprising a hollow outer member, an intermediate member carried by and extending into said outer member to form a water-receiving compartment therebetween, said intermediate member having an opening in its side wall, a tubular member surrounding said opening and extending into the interior of the outer member, a bowl carried by said intermediate member and communicating near its bottom with the interior

thereof, and a hollow stem removably carried by said hollow member, the smoke remaining above said water on its passage through the pipe.

2. A smoke pipe comprising a hollow outer member, an intermediate member to form a water-receiving compartment therebetween carried by said outer member and having an opening in one of its sides adjacent its upper end, a short tubular member surrounding said opening and sloping downwardly into said outer member for communicating with the interior of said outer member, a bowl removably carried by said intermediate member and communicating near its bottom with the interior thereof, and a hollow stem removably carried by said outer member, the smoke remaining above said water on its passage through the pipe.

3. A smoke pipe comprising a hollow outer member, an intermediate member carried by and extending into said outer member to form a water-receiving compartment therebetween, said intermediate member having an opening in its side wall, a tubular member surrounding said opening and extending into the interior of the outer member, a bowl carried by said intermediate member and communicating near its bottom with the interior thereof, and a hollow stem removably carried by said outer member, said stem having a tubular member extending therefrom and into said hollow outer member, the smoke remaining above said water on its passage through the pipe.

4. A smoke pipe comprising a hollow outer member, an intermediate member to form a water-receiving compartment therebetween carried by said outer member and having an opening in one of its sides adjacent its upper end, a tubular member surrounding said opening and extending at an angle thereto into said outer member for communicating with the interior of said outer member, a bowl removably carried by said intermediate member and communicating near its bottom with the interior thereof, and a hollow stem removably carried by said outer member, and having a tubular member extending therefrom and into said hollow outer member, the smoke remaining above said water on its passage through the pipe.

In testimony whereof I have affixed my signature.

EMIL M. SPRICH.
